CIRCULAR KNITTING MACHINE

Julius Sirmay, Philadelphia, Pa., assignor to
 Jacquard Knitting Machine Co., Inc., a corpora-
 tion of New York

Application June 5, 1930, Serial No. 459,339

10 Claims. (Cl. 66—20)

This invention relates to circular knitting machines having a plurality of beds for cooperating intermeshing needles, of which the well known dial-and-cylinder machine is illustrative. For conciseness machines of the kind indicated are 5 herein referred to as "circular rib machines".

Among the objects of the invention are:

To provide an improved arrangement for knitting plain fabric of two or more different stitch- 10 relations between the dial stitches and the cylinder stitches composing it; for example, for knitting 1:1 fabric alternately with 2:2. The invention is not limited to either 1:1 or 2:2 however nor to these two together, nor is it limited 15 to the production of a fabric or fabrics of only two stitch relations, as will become apparent.

To provide an improved machine for knitting patterned fabrics, as well as plain fabrics of two or more different relations between their dial 20 stitches and their cylinder stitches.

To provide for the production, on circular rib machines, of such patterned goods wherein individual rows of stitches in the face or patterned side of the fabric are composed in part 25 of stitches formed of one yarn and in part of stitches formed from another or other yarns, and having for their opposite side or back the so-called "twill back" and/or "birdseye back", without however the back seeming to be divided 30 into sections. This feature is also applicable wherever it is desired that the "back" of the fabric be knitted in a more or less regular manner, but where it is desired that the number of stitches knitted by those needles forming the 35 "back" shall, in each rotation of the cam cylinder or dial cam carrier for example, be less than the product of the number of needles in the needle bed on which the back is knitted multiplied by the number of yarns employed in 40 forming the pattern or other fancy effect on the face of the fabric. Back-formations of this type are herein referred to as "reduced-stitch backs."

To provide for the production of reduced-stitch 45 backs in machines adapted also for knitting plain fabric having two or more different relations between its dial stitches and its cylinder stitches.

To provide in a machine arranged to produce 50 patterned goods alternately with plain ribbed goods, and having yarn changers, mechanism to assure the new yarn being taken by the cylinder needles when the yarns are being changed.

To improve circular rib knitting machines in 55 still other respects.

And, by combining more or less of the foregoing

features, to provide a circular rib knitting machine adapted to knit complete garment-length fabrics having plain knit borders different from the plain knitting in the bodies and patterned in the bodies as desired.

The manner in which these various features are accomplished appears hereinafter.

The accompanying drawings illustrate a highly developed form of knitting machine embodying all the foregoing to the common end of providing a machine adapted to knit complete garment-length fabrics self finished at one end.

In these drawings Fig. 1 is a plan view of this machine, partly in section; its racking and dogless mechanism, which is built above the main body of the machine being shown at one side of the latter; Fig. 2 is an elevation of the same machine; Fig. 3 is an elevation of one section of the pattern mechanism. Fig. 4 is a sectional view of one of the pattern mechanism sections and the adjacent portion of the knitting machine; Fig. 5 is an elevation of one of the yarn changing mechanisms; Fig. 6 is a plan view of the latter, and also showing mechanism for moving one of the dial cams into and out of operation; Fig. 7 shows similar mechanism for another dial cam; Fig. 8 is an elevation of one of the yarn guides; Fig. 9 is a plan view of the dial cams of two feeds of the machine; Fig. 10 is a sectional view of one of the trick wheels or skip operators of the dial needles employed in the production of reduced-stitch backs; Fig. 11 is a face view of a part of the wheel or operator of Fig. 10; Fig. 12 is a front elevation of a latch opener for needles of the dial; Fig. 13 is a side elevation of this latch 30 opener, at right angles to the showing of Fig. 12, and also showing a guide for holding the dial needles in place in their slots at the point where their latches are opened; Fig. 14 is an elevation of one of the mechanisms employed for raising and lowering the stitch cams of the cylinder needles; Fig. 15 is a sectional view of the mechanism of Fig. 14, the joint operation of a related stitch cam of the dial needles being also shown in this figure; Fig. 16 is a plan view of a detail 35 of the operating mechanism of Fig. 14; Fig. 17 is a sectional view illustrating the different length needle butts employed and also showing one of the cams for projecting the dial needles; Fig. 18 is a sectional view illustrating one of the thin cylinder needle raising cams and its 40 operation with respect to long and short butt needles; Fig. 19 is a section illustrating one of the thick cylinder needle operating cams; Fig. 20 is a plan view of one of the mechanisms here 45

55

employed for raising and lowering the cylinder needle raising cams; Fig. 21 is an elevation of the subject matter of Fig. 20; Fig. 22 is an elevation, partly in section, of the master controller 5 and the driving mechanism of the knitting machine. Fig. 23 is a section through the driving mechanism of the machine as indicated by the arrow and section line on Fig. 22. Fig. 24 is an elevation of a pin wheel of the pattern mecha- 10 nism.

The multiple feed circular ribbed knitting machine chosen to illustrate the invention is a four feed machine, the feeds being generally 15 denominated by the letters A, B, C, and D in Fig. 1. The upper bed plate 1 and lower bed plate 2 of the machine can be assumed to be supported by legs in some well-known manner. The needle cylinder 3 and dial 4 are stationary, 20 the cylinder 3 resting on the bed plate 2 and the dial 4 being suspended on the post 6 in the usual manner; the manner in which the dial 4 is held stationary with respect to the cylinder 3, by bracket 7 rising from bed plate 1, is discussed later. The needle cylinder is surrounded 25 by the usual (and here rotating) cam cylinder 8 from which a bracket 9 rises and drives the dial cam carrier 10 through the link 11 in quite an ordinary manner. So far as a part of the 30 invention is concerned, the cam cylinder 8 can be driven in various known ways; the manner in which it is driven by preference, in view of the various types of fabrics producible on it, is described later.

In order to produce a fabric (or fabrics) having 35 different relations between its (or their) dial stitches and cylinder stitches (for example, to produce plain 1:1 fabric alternately with plain 2:2 fabric) I employ a multifeed machine. At, say, one of the feeds, A, I arrange for knitting 40 on such a certain limited lot of the needles of at least one of the needle banks (dial or cylinder) as will produce fabric of one of the desired stitch relations. At, say, another feed, B, I provide for knitting on such another lot of the needles (of 45 the same or the opposite bank) as will produce fabric having the second desired stitch relation. Likewise at a third and other feeds if a fabric (or fabrics) of three or more different stitch relations are desired. Where necessary or desirable (as will frequently be the case 50 and as is illustrated by the machine shown in the accompanying drawings) different lots of needles of both the dial and the cylinder (rather than of only one of them as above suggested) can be 55 knitted on at the different feeds. Also as shown in the machine here illustrated, where the machine has more feeds than there are different stitch relations to be produced, two or more feeds, such as feeds A and C, can be used to 60 produce fabric of one stitch relation and, say, two or more other feeds, such as feeds B and D, can be employed to produce another stitch relation, etc. In general then, I so arrange or 65 construct the machine that each stitch relation is the individual product of a certain feed or feeds. One or all the feeds producing one of the desired stitch relations, is so constructed of course that it or they can be held out of action while another or other feeds is or are operating. 70 Generally speaking, the differing and individual actions at the various feeds during plain knitting, can be obtained in various ways. With individually sliding needles however, I preferably employ needles differing among themselves in 75 form (for example, long and short needles,

needles having long and short butts, etc.; note needles 13 and 14 in Fig. 17), and therewith, preferably, at the different feeds of the machine, employ cams to slide the needles which differ among themselves, in, say, shape, thickness or location to such an extent that one cam is capable of engaging and sliding needles of one form, and another cam needles of another form, etc. In the present instance the machine illustrated is shown set up for making 1:1 plain fabric alternately with 2:2 plain fabric; in the dial (see Fig. 9) long butt needles 13 are arranged in pairs, each pair being followed by a short butt needle 14; likewise in the cylinder long butt needles 18 are arranged in pairs, each pair being followed by one short butt needle 19 (Fig. 18); at feeds A and C thin cams 20 (Fig. 17), deep enough to engage only the high butts, are used to project the (high butt) dial needles 13 to clearing positions (loops behind the latches), and thin cams 21, engaging only the high butt cylinder needles 18, serve to project the (high-but) cylinder needles to clearing positions; in feeds B and D, the dial projecting cams 22 and the cylinder projecting cams 23 are thick enough to project the low butt needles 14 and 19 to clearing positions, as well as the high butt needles 13 and 18. The dial cams 20 and 22 are hinged to the dial cap 10 for individual movement into and out of action; also the cylinder cams 21 and 23 are 30 slidable into and out of action. Consequently when cams 20 and 21 are in operation (positions shown in Figs. 9 and 19) and cams 22 and 23 are retracted or out of operation (dotted line positions in Figs. 9 and 21) 2:2 fabric is knitted at 35 feeds A and C; reversely when dial and cylinder cams 22 and 23 are in action (positions in Figs. 9 and 18) and cams 20 and 21 are displaced from operative position, 1:1 fabric is made by feeds B and D. Obviously (assuming that the 40 hereinafter described additional mechanism that is provided for projecting the needles to clearing positions is temporarily rendered ineffective also) the retraction of cams 22 and 23 discontinues the casting-off of loops at feeds B and D (by discontinuing the clearing or placement of the loops behind the needle latches at these feeds) and hence feeds A and C are permitted to 45 knit substantially as though feeds B and D were not present in the machine; likewise the retraction of cams 20 and 21 discontinues casting-off at feeds A and C and permits knitting at feeds B and D substantially as though feeds A and C were absent. Usually I so place the cylinder raising cams 21 and 23 that the cylinder 50 needles reach, or at least stand in, their clearing positions about opposite the points of the dial projecting cams 20 and 22 respectively, as indicated in Fig. 9. The four cylinder stitch cams 25 are so placed that they bring the cylinder needles to their lowest positions substantially opposite the points on the machine where the dial stitch cams 26 retract the dial needles the farthest. At least at that or those feeds (B and D) where 1:1 fabric is knitted, I usually 55 provide another dial stitch cam 24 somewhat to the rear of the stitch cam 26; by mounting the cams 26 for movement into and out of operating position (as by hinging them to the dial cap 10 as shown) any of the cams 24 or 26 can be used as desired. All the stitch cams 24, 25 and 26, are thick enough to engage the low butt needles as well as the high butt needles. Usually 60 when making 2:2 fabric (at feeds A and C) I use the stitch cams 26; and usually when mak- 65 70 75 80 85 90 95 100

ing 1:1 fabric (at B and D) I employ the stitch cams 24 rather than 26, the cams 24 then making a tighter fabric than 26. When any feed is to be out of action for any considerable time, the feed of yarn at that feed will be discontinued of course. Obviously various controller mechanisms, simple or complex, and manually or automatically operated, can be employed for putting the various cams already mentioned into or out of action. Preferably I use those illustrated. A pair of finger levers 28 and 29 serve to position each of the dial needle projecting cams 20 and 22. From each of the dial cams (see Fig. 6) a pin rises through a slot in the dial cap 10 and rests in a slot in a bell crank lever 27 mounted to turn freely on a pin or shaft 93 rising from the dial cap. The finger lever 28, also hinged on the dial cap and projecting beyond the edge of the latter, has a pin resting in another slot of lever 27; a spring 28^a, fastened to this pin and the dial cap, tends to turn this lever system in such a direction as to take cam 22 (or 20, as the case may be) out of action. The second finger lever 29, hinged to the dial cap and also projecting beyond the edge of the dial cap, has a shoulder to engage a shoulder of lever 27 in such a manner as to resist the action of spring 27^a, and thereby hold cam 22 (or 20) in action; a spring 29^a urges lever 29 to this holding position. The projecting end of the finger lever 28 of each feed is at a slightly different level from the companion lever 29; all the levers 28 are in one level, and all the levers 29 are in another. A bob pin 127, rising from the bed 1 of the machine, serves to knock over the levers 28 and 29 alternately as the rotating dial carries them by the bob pin. This bob-pin has three positions; the lowest, below the path of all the levers 28 and 29; the middle position, in the path of say the lever 28; and the highest position, in which it is in the path of the levers 29. By putting the bob pin 127 in the path of the appropriate finger lever 28 or 29 of any one feed just before that feed reaches the bob pin, (or leaving it in that position if already so positioned), the position of the corresponding cam 20 or 22 can be changed, as will be apparent. Each of the projecting (raising) cams 21 and 23 for the cylinder needles is carried by its own bolt 30 mounted to slide vertically in the cam ring 8 (Figs. 18, 19 and 21). An individual toggle 31 is hinged at one end to the head of each bolt 30 and also to the side of the cam cylinder 8; an individual finger lever 32, hinged at the top of the cam cylinder 8 (Fig. 20) and projecting down over the latter a little way, serves (when thrust to the left from its position in Figs. 20 and 21) to straighten out its associated toggle and thus raise the cam 21 or 23 of that feed to operating position; in doing this it passes the joint of the toggle slightly beyond the center line and rests it against the bell crank lever 33 (moving the lower end of the latter to the left from its position shown in Fig. 21) so that the toggle then serves to hold the respective cam 21 or 23 elevated and in action until the joint is thrust to the left again. The upper end of bell crank lever 33 (which is hinged to the side of cam cylinder 8 as shown in Fig. 21) projects into a finger lever 34 hinged to the top and projecting from cam cylinder 8, whence it is apparent that by turning this lever 34 clockwise in Fig. 20, the lower end of the bell crank lever 33 is made to thrust the toggle joint over its center line to the left, whence the respective cam 21 or 23, being no longer supported by the toggle is thrust down out of action by the pressure of the needle butts striking it. The toggle joint in thus moving to the right, returns finger lever 32 to about its position shown in Figs. 20 and 21. The outer ends of all the finger levers 34 (one for each feed) stand in one level, which is somewhat higher than the level of the lower ends of the finger levers 32. A bob-pin 35 serves to knock over all the finger levers 32 and 34. This bob-pin has three positions; in its lowest position it is below the path of finger levers 32; in its middle position it stands in the path of the finger levers 32; in its highest position it stands in the path of the finger levers 34. Hence by raising this bob pin 35 to its middle or upper position just prior to the passing of any feed, the appropriate finger lever 32 or 34 of that feed can be knocked over (to the left in Figs. 20 and 21) and thereby the cam 21 or 23 of that feed repositioned. Each dial stitch cam 26 and its associated cylinder stitch cam 25 (of the same feed) will usually need to be, or without harm can be, shifted together; hence a single mechanism will serve to put these two stitch cams of each feed into and out of action. Further, it is commonly desirable that these stitch cams be adjustable to draw either long or short stitches; that is to say, have two operating positions as well as an inoperative position. The mechanism I have devised for shifting these stitch cams 25 and 26 has both these positions. It will be understood that there is one of these mechanisms at each feed, and each is capable of shifting its cams 25 and 26 independently of all the others. Referring particularly to Figs. 6, 9, 14, 15 and 16: a pin 42, rising from each of the cams 26 through a slot in the dial cap 10, rests in a slot in a lever 44 hinged to the dial cap and provided with a spring 45 tending to swing its cam 26 outwardly to its inoperative position. On the cam cylinder 8, each of the stitch cams 25 is carried by a slide 37 which is provided with a cap 39 having two surfaces 40 and 41 at different elevations for engagement by the two threaded pins 46 and 47 carried (and independent and adjustable) in the bracket 48 which is fastened to the rock shaft 49 mounted in the cam cylinder 8 another bracket 18 also carries two (independently adjustable) threaded pins to engage and shift the lever 44 and thereby the dial stitch cam 26. The lower end of the shaft 49 is geared to a parallel shaft 49^a, and the two shafts 49 and 49^a are provided with the finger levers 148 and 149 respectively, projecting outwardly from the cam cylinder. As appears from Fig. 15, the lever 148 is undercut and the lever 149 is overcut to provide adjacent shoulders, but otherwise these two levers are alike. All (four) of the levers 148 are at a single level; also all (four) of the levers 149 are at a single, but lower, level. A bob pin 77 is provided to be struck by and knock over these finger levers as it may be raised into their paths. This bob pin 77 has four positions; in its lowest position (illustrated in full lines in Fig. 15) it is entirely below the level of these finger levers; at its next higher position it is in the path of the lower finger levers 149; in its highest position (illustrated in broken lines in Fig. 15) it is in the path of the finger levers 148; in its middle raised position, the bob-pin 77 is in the paths of the shoulders of both (all) the finger levers 148 and 149. A lever 148 striking the bob pin 77 when the latter is in its highest position

tion, is thereby knocked over to the position of 148 in Fig. 9; pin 47 then rides up on surface 40 and thus thrusts the corresponding cylinder cam 25 to its lowest position, and one of the 5 threaded pins in bracket 78 thrusts cam 26 to its innermost position. A lever 149 alone striking the bob pin (the latter being at its first position above its lowest or inactive position) is thereby knocked over to the angular position in 10 which 148 is shown in Fig. 9; both pins 46 and 47 are thereby taken off the head 39, and both the pins of bracket 78 are moved off lever 44; cam 25 then rises to its inactive position and cam 26 moves to its outermost and inactive position. 15 When however bob pin 17 is so placed as to be struck by the shoulder of whichever finger lever 148 or 149 may be outermost at the time, both these finger levers are moved to positions midway between 148 and 149 of Fig. 9, and 20 thereby pin 46 is placed on surface 41 of head 39 and the right hand pin (Fig. 9) of bracket 49 bears on lever 44; the cams 25 and 26 now retract their needles but not so deeply as before.

I prefer knitting plain fabrics of different 25 relations between their dial and cylinder stitches, at different feeds as indicated and especially producing these different-stitch-relation fabrics by means of cams, both because of the comparatively simple construction involved and because 30 pattern and related mechanisms are then readily applied to either the dial or cylinder needles or both. While I prefer to employ a true jacquard type of pattern mechanism as is here shown applied to the cylinder needles (because of the 35 elaborateness of the patterns and other fancy effects that this type of pattern mechanism can produce), it will be apparent from the description of the application of this jacquard type of mechanism that other types of pattern and analogous mechanisms can be employed as well, 40 either for the dial needles or the cylinder needles or both. The type of pattern mechanism here employed is well known, and causes the cylinder needles to knit from the yarns of the various 45 feeds in such a selective manner as the fancy effect desired may require. This pattern mechanism is divided into a number of sections distributed around the machine (Fig. 1) and for say each feed a cylinder needle raising cam is provided on the secondary cam ring 54 carried on 50 the lower bed 2 (Fig. 4); these needle raising cams are placed in the same angular positions as the cams 21 and 23; the ring 54 is driven synchronously with the main cam cylinder 8, and 55 the cams 21 and 23 are all depressed out of action while the pattern mechanism is in use. The stitching on the dial is done by the cams 26. Each section of the pattern mechanism consists of a pattern drum 50 mounted in brackets 51 carried by the lower bed plate 2, and a group of thin metal levers 52, say one for each needle, provided with feelers 53 to engage a paper or like pattern carried by the drum 50. The inner ends of these levers 52 rest on the cam ring 54 in the 60 path of the needle raising cams thereon previously mentioned; at their outer ends they are slotted and through the slots of each group passes a carrying rod 55 held in the brackets 51 of the respective section. In their outermost positions 65 illustrated in Fig. 4, in which positions they are held normally by the individual lever springs 56, these levers do not reach quite underneath the needles 18 or 19; if these needles 18 and 19 are not long enough to reach down to the level of 70 the levers 52, jacks 57, say one for each needle,

may be provided as will be understood. In general jacks, for example such jacks as at 57, placed below or behind needles (which here are representative of stitch-forming elements), constitute extensions and in effect parts of the needles as it were, and may be employed wherever otherwise the needles would be inconveniently long or whenever for any other reason jacks may be desirable, all as will be understood. As the cam ring 54 rotates therefore, the needle raising cams on the ring 54 raise the inner ends of the levers 52 in succession, but the levers being in their outer positions, the corresponding cylinder needles are not raised. The drums are turned successively, each say one step just before each of the raising cams of 54 reaches its levers. Where this turning of a drum brings a perforation in its paper pattern underneath a feeler 53, that feeler falls through the perforation into a slot in the drum and the corresponding lever 52 is then moved inward and underneath its respective needle (or needle jack 57). Now the passing raising cam of ring 54 not only raises that lever, but also raises the needle associated with that lever. Accordingly in each pass of each feed those needles whose respective levers 52 find perforations in the paper pattern below them, are raised to take yarn from the yarn guide of that feed, and a stitch is formed therefrom by the following cylinder stitch cam 25; cylinder needles corresponding to levers 52 which do not find perforations below them in any pass of any feed, remain down and do not take yarn from that feed. As soon as a feed passes any section, the levers of that section that were thrust inwardly, are retracted again, say by the springs 56. Each drum 50 is driven by a Geneva wheel 60 fixed to the drum shaft. The pin wheels 61 of the Geneva wheels are driven by gears 62 keyed to the shafts 63, which are also carried by the brackets 51; the various shafts 63 are geared together at their ends by miter gear 78, and at some point this train of shafts is driven from say the ring 54 so as to be driven in the necessary fixed speed relation to the cam cylinder 8 and dial cap 10. This type of pattern mechanism being well known, and being subject to many variations in details of construction, the foregoing description of it will suffice for the present purposes. In order that plain cloth may be made by the use of the cams 21 and 23 above described, alternately with patterned fabric through the use of this pattern mechanism, it is necessary of course that mechanism be provided for putting this pattern mechanism into action and taking it out of action again at will. Means for doing this are already known, but I prefer that shown wherein each pin wheel 61 is mounted on a bracket 65 which in turn is connected to a lever 66 for reciprocation thereby to such a degree as to put the pin wheel into driving relation with its associated Geneva wheel 60 (Fig. 3) or out of driving relation therewith (lower right hand of Fig. 1). Each gear 62 is made so wide-faced that its pin wheel 61 remains in gear with it regardless of whether this pin wheel is in its right or left hand position, and each pin wheel carries with it a sleeve 19 (Fig. 24) which is slotted to permit the teeth of its Geneva wheel to pass only underneath the pin, so that when the pin wheel is out of driving relation with the geneva the sleeve holds the latter against turning; hence both the pin wheels and the pattern drums remain at all times properly timed with respect to the movements of the various feeds around the 75

machine axis. To oscillate the levers 66, each is provided with a yoke 67 containing a three-pointed star wheel 68 mounted on a shaft which also carries a six-pointed star wheel 69; the 5 shaft carrying these star wheels is mounted on the fixed bed plate 1 as shown in Figs. 1 and 4. On the cam cylinder 8 is provided one vertically adjustable finger 70 for turning the star wheels 69 step by step as the cam cylinder 8 rotates 10 and carries this finger by the star wheels 69 successively thereby shifting the pin wheels 61 into and out of action as will be understood. This pin 70 may be mounted on a bracket 71 as shown in Figs. 3 and 4 and the bracket mounted on a 15 vertically sliding pin 72 in the cam cylinder 8. A lever 75 hinged to the cam cylinder, serves to raise the bracket 71 and thus put pin 70 in position to strike the star wheels 69, when the lever 75 is raised by the bob pin 76; when this occurs, 20 a spring pressed lever 73 snaps outwardly under a shoulder of bracket 71 to hold the latter raised to this active position. It will be understood that while one complete revolution of the cam cylinder 8 with the pin 70 raised to active position 25 will serve to turn all star wheels 69 one step each and put all the sections of the pattern mechanism into action, the next revolution of the cam ring with the pin 70 raised to the same position will turn the star wheels another step and thus 30 put the pattern mechanism out of action. After the bracket 71 and its operating pin 70 have been raised, they are lowered again (under the thrust of a spring on pin 72) by the levers 73 striking the bob pin 76, the latter being now dropped 35 down to its low position; the levers 73 are thus knocked back from underneath the shoulder of bracket 71, permitting the latter to fall.

When making patterned fabric by selectively knitting on the cylinder (or dial) needles, it is 40 preferable to knit more or less selectively on the dial (or cylinder) needles also, thereby making the number of stitches forming the back of the fabric less in number than they would be if each dial needle knitted from every pass of every yarn. 45 To this end I not only arrange for the needle projecting cams 20 to be out of action alternately with the projecting cams 22 and vice versa, as needed for the production of fabrics having different relations between their dial and cylinder 50 stitches, but also for having all the cams 20 and 22 out of action together; and I provide other mechanism for projecting the dial needles while pattern work is being done, this substitute mechanism being of such a nature that in any single 55 rotation of the dial cap only a part of the dial needles knit from the yarn or yarns of one feed and the other dial needles knit from the yarn or yarns of another or other feeds. Broadly speaking, various types of mechanisms can be used for 60 bringing about this selective knitting by the needles forming the back of the fabric, and my invention is not limited to any particular type of mechanism for this purpose, broadly speaking. Preferably however, rather than employ any 65 more or less complex pattern mechanism, I employ mechanism which causes a more or less regular selective knitting at the back of the fabric; and preferably at each feed (or rather, preferably, at each of those feeds that are in action 70 when pattern work is being done) a skip operator as I have called it, such as a wheel 80, set rather well in advance of cams 20 and 22, at an angle to both the local radius of the machine and the local tangent of the dial edge, rotated by 75 the dial needles in passing or by the walls of the

slots in which the needles rest, and slotted as at 81 in Fig. 11 so that certain predetermined needles pass through the edge of the wheel without being projected; the needles whose butts strike the wheel intermediate these cuts 81 are then 5 projected to, or at least toward, yarn-taking position. In order that the needles may turn the wheels in passing, the wheels may be notched as 10 at 82 to receive the needle butts of those needles that are to be projected by the wheels. The 15 wheels may be carried on individual stub shafts 83 mounted on the dial cam cap 10 and the latter slotted below the wheels to permit the wheels to reach the needle butts. I find it preferable to so design and locate such wheels that they 20 project the needles only part way to their outermost or clearing positions (say to tuck positions, the butts of the projected needles being placed outside separator cams 84 while the butts of the unprojected dial needles are allowed to pass inside these cams), and add to each a cam 85 to 25 complete the projection of the dial needles to the clearing point; that is to say, to the point where the loops fall back of the needle latches. By mounting each of these cams 85 so that they can 30 be moved into and out of action, and providing at each feed another cam 87 movable into a position where it can restore to their original retracted positions those needles that are partly 35 projected by the adjacent wheel, the effect of each wheel can be nullified at will. These two cams 85 and 87 can be mounted on a single hinged piece 86; when the latter is turned to the position illustrated at the upper right hand of Fig. 9, cam 87 serves to return the partly projected needles to their innermost rest positions in advance of the point where the yarn of the 40 respective feed is fed to the dial needles and in advance of the point where the needle-projecting cam 20 or 22 acts, so that the latter are free to project their needles if desired; on the other hand, when this piece 86 is turned to its outer position illustrated at the bottom of Fig. 9, cam 85 supplements the wheel and projects to clearing 45 position those needles selected for this action by the local wheel 80. Each trick wheel or skip operator 80 may be so cut of course as to project and pass the needles in any desired order, and therefore to bring about almost any desired stitch-formation at the back of the fabric. 50 Usually however I make the number of needles in the dial a non-multiple of the sum of the needles skipped by one of the wheel slots 81 plus the number of needles engaged by the wheel between two slots; for example, if a wheel is cut 55 to skip every third needle and project the intervening two needles, I would usually use in the dial such a number of needles that the number thereof is not a multiple of three; as a result, speaking generally, a needle projected by a given 60 wheel in one round is skipped by the same wheel in the next round of the dial cap. Also usually at least when yarns of two or three or four colors are used in making the pattern effect on the face of the fabric, I cut or slot the wheel (at 81) in 65 such a manner that each wheel projects every second needle; so far as possible, usually, I so arrange the wheels that each projects needles which the preceding wheel left unprojected. And at least when the pattern or fancy effect is composed of an odd number of colors fed to the needles at an odd number of feeds, I use an uneven 70 number of needles in the dial in order to equalize the number of stitches knitted on the various dial needles. With such an arrangement of the trick 75

wheels or skip operators 80, fabric having the pattern worked out on its face in three colors, has the so-called twill back or birdseye back. In order to prevent the reduced-stitch back (whether produced by such wheels 80 or by other mechanism) from appearing to be divided into sections (which sectionalization is more or less pronounced depending on the contrast between the colors employed) I bring all the mechanisms for producing the reduced-stitch back into action at preferably some one point around the needle cylinder, or at two diametrically opposite points when, say, the tubular fabric is to be cut longitudinally at two diametrically opposite points. To this end, I have provided a single bob-pin 127 for taking the dial needle projecting cams 20 and 22 out of action, as before described; and I preferably use but a single bob pin 99 (or bob pins located at a single place) for swinging the cam members 86 into the position illustrated at the bottom of Fig. 9, in which position they bring about the knitting of the reduced-stitch back. As with respect to the other adjustable position cams of the machine, various kinds of mechanisms can be used to shift the cam members 86 from one position to another, but preferably I employ the mechanism illustrated in Fig. 7. This mechanism (at each feed) includes a gear 90 fastened to the pin or shaft 91 by means of which the cam member 86 of the respective feed is hinged to the dial cap 10; co-operating with it is another gear 92 fast on the shaft 93 rising through the dial cap 10. Above the finger levers 28 and 29 (see Fig. 6) which operates the adjustment needle projecting cam 20 or 22, an arm 94 is fastened to the upper end of the shaft 93 and this arm has a pin and slot connection with a rock arm 95 fastened to a rockshaft 96 rising from the cam cylinder 8. Below the finger levers 28 and 29 a finger lever 97 is fastened to the rock shaft 96, and the oppositely operating finger lever 98 is geared to this rock shaft. All (four) of the finger levers 97 are at one level and all (four) of the finger levers 98 are at another level. The finger levers 97 and 98 are knocked over as required by the single bob pin 99. The latter has three positions. In the lowermost it is below the fingers 97 and 98; in its middle position, it is within the reach of say the fingers 97; in its highest position it is within the path of the finger levers 98. Therefore by raising the bob pin 99 from its lowest position to either one of its other positions just before any feed comes opposite the bob pin, the cam member 86 of that feed can be moved from its outer position shown at the bottom of Fig. 9 (in which position reduced-stitch back is knitted) to its inner position shown at the upper right of Fig. 9 (in which position the action of the associated wheel 80 is nullified) or vice versa. The wheel 80 and various associated cams somewhat as described above, constitute the subject matter of my copending application Serial No. 454,856 filed May 23, 1930; however I herein claim subject matter related thereto which is herein illustrated and described, and which is not disclosed in my said copending application.

Where for example say a 2:2 bottom is to be knitted (say at one end of each garment-length piece of fabric) it is usually desirable that this bottom be knitted either of a relatively heavy yarn or that an additional end of yarn be knitted in to reinforce this bottom. Consequently at the feed or feeds where the 2:2 is knitted (e. g., at feeds A and C) I employ a yarn changer capable

of feeding any one of two or more yarns, so that this or these feeds can be used also for knitting patterned fabrics as before described. The use of yarn changers at the other feed or feeds is optional, generally speaking, depending, for example, on the number of yarns which the constructor desires to make available. Furthermore this heavier-yarn or reinforced bottom (due to its being thicker than the body of the fabric) is the cause, I have found, of a certain irregularity in the knitting found in fabrics incorporating say both 1:1 and 2:2 when made on circular rib knitting machines wherein dogs on the cylinder and dial are employed to hold the dial against rotation with respect to the cylinder. Accordingly, in my machines adapted to make fabrics having different relations between their dial and cylinder stitches I employ a dogless mechanism for holding the dial against rotation with respect to the cylinder. Obviously any of the various dogless mechanisms that have been devised heretofore may be employed. The dogless mechanism illustrated will serve for illustrative purposes, and has the advantage in that it incorporates an improved form of racking mechanism as well. The racking feature can be employed in producing fancy effects in the fabric, or for making a finished edge, or both, as will be understood. In this dogless mechanism, the post 6 to which the dial 4 is fixed, is keyed or otherwise fastened against rotation to a member 102 which is carried by a bracket 103 mounted on the posts 7 rising from the bed plate 1 (see Figs. 1 and 2). Above this bracket 103 rises the standard 104 on which the yarn cones are carried and a circular member 105, also carried by the bracket 103, and driven with the cam cylinder 8 and dial cap 10 by means of the connection 106 is pierced at 107 (where it is connected to standard 104) outside the member 102 to permit the yarns to pass through it from the cones. In known manner, a number of sliding latches 108 serve to lock the circular member 102 to the fixed bracket 103, these sliding latches being actuated by a cam race 101 in the rotating member 105 in such a manner as to permit the yarn holes 107 to pass the latches. This general type of dogless mechanism is well known, and the foregoing description will therefore serve the present purposes. Known racking mechanisms of various kinds may also be used, though I prefer to rack the dial as a whole rather than by sections racked successively. Preferably to this end the member 109 of the bracket 103 into which the sliding latches 108 project for locking the member 102 and post 6 against rotation, is itself mounted for more or less rotation in the body of the bracket 103, and mechanism is provided for rotating, or at least oscillating, this member 109 thereby racking the dial accordingly. For this purpose, the member 109 is preferably provided with gear teeth in its outer edge, these teeth gearing with a worm 110 fastened to the Geneva wheel 111, by gears 112 and miter gear 128 the horizontal shaft 113 is driven constantly from the member 105 of the dogless mechanism, and the shaft 113 is provided with clutch mechanism for throwing either the pin wheel 114 or pin wheel 115 into operating relation with the Geneva wheel 111, these two pin wheels being rotated in opposite directions on and by the shaft 113. This result may be secured by mounting the pin wheel 114 for direct drive by the shaft 113 and mounting the pin wheel 115 on an outer hollow shaft driven in the opposite direction by the miter gear 75

116, and providing a cam track 117 for sliding the two pin wheels along the axis of the shaft 113. Briefly, three pins 118, 119 and 120 are provided for sliding these pin wheels; when pin 119 projects into the cam race 117, as shown in Fig. 5, both pin wheels are held out of engagement with the Geneva wheel 111 as there shown; when pin 119 is retracted and pin 118 is thrust into the cam race obviously pin wheel 115 is pulled upwardly (in Fig. 1) and engages the Geneva wheel 111; likewise when pin 119 is retracted and pin 120 is thrust into the cam race 117, pin wheel 114 is thrust into operating relation with the Geneva wheel 111. Pin 119 is connected to both pins 118 and 120 for operation reversely thereto; pin 118 is thrust inwardly by striker 121 operated by shaft 122 which in turn is rocked at will by the vertical link 123; likewise pin 120 is thrust inwardly at will by the striker 124 mounted on rock shaft 125 which is rocked by the vertical link 126. The slotting of the Geneva wheel 111 and the pitch of the threads of the worm 110 are such preferably that one rotation of either pin wheel 114 or 115 is sufficient to rack the dial the distance of one needle.

When racking the whole dial, it is necessary of course that none of the dial needles be left projecting between the cylinder needles (or reversely, that none of the cylinder needles be left projecting between dial needles) at the time of the racking operation. To this end prior to racking all the cylinder raising cams 21 and 23 can be lowered out of operation by mechanism previously described, and thus this result secured. Preferably, however, I add a safety mechanism to assure all the cylinder needles (or dial needles) being held retracted during racking. For this purpose, I surround the links 123 and 126 which direct the racking operation with a yoke 130 and provide each of the links with its own pin 131 to support this yoke; normally this yoke is held downwardly against these pins by the spring 132. One face of the yoke 130 is cammed (as shown in Fig. 2) and in its lower position this yoke 130 holds lever 133 in the broken line position illustrated in Fig. 20; this lever is hinged at 134 to the top of the base plate 1 and is pulled against the yoke 130 by a spring 135. At each feed, a finger lever 137, engaging with a pin 139 arising from the link 136 which is mounted on the adjacent finger lever 34 previously described and a companion lever also hinged to the top of cam cylinder 8 (Figs. 20 and 21), is fastened to a rock shaft 144 mounted in the cam cylinder 8 and at its lower end having a yoke 145 engaging with a pin 146 rising from an oscillating ring 140 carried on the horizontal foot of the cam cylinder 8; in turn the ring 140 carries, at each feed, a finger 142 normally resting against the adjacent toggle 31; one or more springs 141 tend to move the ring 140 in the direction to bring fingers 142 toward the toggles 31. From this construction, it is evident that when either of the racking rods 123 and 126 is raised to bring about racking of the dial, the yoke 130 is raised therewith and the cammed face of this yoke then permits the lever 133 to move to its full line position in Fig. 20. In this position, it is struck by the first of the finger levers 137 that is brought opposite it by the rotation of the cam cylinder 8; this finger lever 137 is thereby turned counterclockwise (Fig. 20) and by its engagement with its pin 139 it thrusts the link 136 to the left, thereby causing adjacent lever 33 to break the toggle 31 of that feed. At

the same time, this same lever 137, operating through its rock shaft 144 and yoke 145, turns the ring 140 in the counter-clockwise direction (Fig. 20), and this rocks all the other rock shafts 144 of the whole machine; thereby the links 136 and levers 33 of all the feeds are simultaneously operated to break all the toggles 31 and drop all the cylinder raising cams 21 and 23 simultaneously. When the cams 21 and 23 (or any one of them) are held up in operating position, the engagement of one of the fingers 142 with a toggle 31 holds ring 140 and thereby all the finger levers 137 in such position that the latter can strike lever 133; when all these cams are down however, the broken toggles permit the ring 140 to rest so far in the clockwise direction (as viewed in Fig. 20) that all the levers 137 are out of the reach of 133.

As before pointed out, a machine arranged for the production of a plain fabric (or fabrics) having two or more relations between the dial stitches and the cylinder stitches, and especially where the machine is arranged for pattern work also, usually requires a yarn changer at at least one feed in order that an extra heavy or an added reinforcing yarn can be employed in one (or more) of the plain fabrics. Furthermore, where the whole dial is racked as a unit and the cam cylinder 8 and dial cam cap 10 continue in operation during the racking operation, it is desirable that all the yarn feeders be so constructed that all the yarns can be held out of action during the racking movement; otherwise the knitting should be continued on one bank; ordinarily it can not be continued on both banks however, during the racking movement. The yarn changing and scissors arrangement shown in Figs. 5 and 6 is illustrative of the type intended, and which can be used at each and every feed. Each of these is mounted on a bracket 150 rising from the dial cap 10 and has a number of yarn fingers (say two, 151 and 152) swinging loosely on the hinge pin 153. Above the level of this hinge pin 153, individual pivoted finger levers 154 and 155 serve to throw the yarn fingers into inactive position (yarns out of action); finger lever 154 thus serves yarn finger 152 and finger lever 155 serves yarn finger 151. Below the level of the hinge pin 153, other finger levers serve to throw the yarn fingers into action, 156 and 157 serving the yarn fingers 151 and 152 respectively. The combined scissors and yarn holder 158 serves the yarn of finger 151 and scissors and holder 159 serves the yarn from yarn finger 152. These scissors and yarn holders are opened by the respective levers 160 and 161, and are closed by their individual springs 162; projecting finger levers 163 and 164 operate the vertical levers 160 and 161 and thereby the scissors and yarn holders. A bob pin 165 carries head 166 to operate the finger levers 154 and 155, and also carries head 167 to operate the scissors finger levers 163 and 164 in co-operation therewith. In the lowest position of bob pin 165 (shown in Fig. 5) heads 166 and 167 are out of operation; in its middle position, 166 is in position to be struck by finger lever 155 (as the rotation of the dial cap 10 carries the respective feed past the bob pin) and the head 167 is in position to be struck by the corresponding scissors finger lever 163; in its uppermost position, head 166 is in position to be struck by the finger lever 154 (assuming this finger lever to be in its outer position) and head 167 is in position to be struck by the corresponding scissors finger lever 164. In like man-

ner, and operating in the same way, the bob pin 168 is provided with two heads 169 and 170 co-operating respectively with the finger levers 156—157 and 163—164. Hence by raising the 5 bob pins 165 and 168, either or both yarns can be put into or taken out of action at any or all feeds.

If desired, as it usually will be in such a highly developed machine as that illustrated, a cast-off 10 cam can be added; that is to say, a cam located at a place where no yarn is fed and movable at will into a position where it can project needles to cast-off position. On the bracket 171 (Fig. 1), which is like bracket 71 previously described and 15 has levers like 73 and 75, such a cam is carried. By locating this in a quadrant of the machine other than that containing bracket 71, both can be operated by the same bob pin 76.

The bob pins previously referred to can be located at various places around the needle cylinder of course and controlled and operated by various mechanisms. Preferably however these bob pins, and also the racking links 123 and 126, are collected at one station into what I call a master 25 controller, and the whole operated by some such mechanism as illustrated, which permits the use of a perforated pattern 186 of paper or similarly light flexible material as the controlling element, and which can be brought into action from time 30 to time, as required, by a pattern chain 197 for example. In the present instance, the bob pin 76 is arranged to be thrust upwardly by the bob pin rod 175 (Fig. 21) bob pin 127 by rod 176; bob pin 35 by rod 177; bob pin 99 by rod 178; yarn 35 changer bob pin 168 by rod 179; the two rods 123 and 126 serve the racking mechanism as before pointed out; yarn changing bob pin 165 is thrust upwardly by rod 180; and bob pin 77 by rod 181. Each of these rods is provided with as many rods 40 raising or control levers 184 as the bob pin of the corresponding rod has operating positions (positions above its lowest or inoperative position). Thus the racking rod 123 has but one upper position (in which it thrusts the striker 45 arm 121 against the pin 118), and hence but one lever 184 is provided for rod 123; again, rod 181, which controls the position of dial stitch cam 26, has to have three operating positions and hence is provided with three of these levers 184. 50 Each of these levers 184 is provided with a feeler pin 185 resting on the control pattern 186, and its other end is slotted to embrace a rod 187 (Fig. 2) carried by the bracket plates 188 supporting the master controller mechanism from 55 the lower side of the bed plate 2. Individual springs tend to hold these levers in their outer positions (the positions in which they are shown in Fig. 2) and a deep notch 199 in each of these levers permits the lever 190 (hinged at 187) and 60 its cross-bar 191 (extending beneath all the levers 184) to oscillate without turning these levers 184 on the rod 187 so long as the levers remain in this outer position. However, when a perforation 65 pattern 186 comes underneath one of the feelers 185 and the feeler falls through it into a slot in the pattern drum 189 so that the drum in turning a further step, or part of a step thrusts the corresponding lever 184 to the right in Fig. 2 or toward the axis of the needle cylinder, the subsequent 70 swinging of the lever 190 thrusts the cross-bar 191 against the under side of that lever 184, raising its outer end, and thereby raises the controller rod standing above the respective lever 184 and the bob pin, if any, associated with that 75 lever; and the distance raised corresponds to the

vertical depth of the respective lever immediately above the point where the bar 191 strikes it. By suitable timing of the controller drum 189 and the swinging of the lever 190, this raising of a bob pin is made to occur just before a feed reaches the control station, and by a further timing of the lever 190 the bob pin is held raised while the feed passes. Hence by rotating the drum 189 (when in action) at such a speed that the controller pattern 186 makes four calls on the row of feelers 10 in each rotation of the cam cylinder 8, and by thrusting the cross-bar 191 upwardly a corresponding number of times, any bob pin can be made to act on any feed at any time; and by using beneath any rod two or more levers 184 15 having different appropriate vertical depths above the point where the cross-bar 191 strikes them, that rod can be raised at any time to any one of two or more heights. By this means the raising of the various bob pins to the various 20 heights hereinbefore prescribed is brought about. The controller mechanism is driven by miter gear 196 (Fig. 22) which meshes with a gear on the train of shafts 63 driving the pattern mechanism sections, and hence the controller is driven 25 in proper timed relation with the cam cylinder 8 and dial cap 10. The function of the pattern chain 197 is to permit the controller drum 189 to remain at rest except substantially while changes are being made by the master controller, thus 30 permitting the use of a relatively short controller pattern 186. To this end, gear 196 drives (through 199 and 200) a shaft carrying the broad-faced gear 201; incidentally, this gear 201 is attached to a rotating cam 202 on which bears 35 a roller 203 carried by the lever 190 and which thus serves to oscillate the lever 190 and its cross-bar 191. The controller drum 189 is driven by a Geneva wheel 204, and the latter in turn is driven by the pin wheel 205 which is carried 40 by a sleeve having a V-shaped cam 206 shown particularly in Fig. 22; this sleeve is slidable parallel with its own axis, and the gear 201 is sufficiently wide-faced to permit the pin wheel 205 to remain meshed with it, and driven by it, 45 when the pin wheel is in its out of action position (illustrated in Fig. 22) as well as when it is somewhat further to the right where it cooperates with the Geneva wheel 204 to turn the control drum 189 step by step. The pattern 50 chain 197 is carried on the sprocket wheel 220 to which is fastened a ratchet wheel 207. In order that the chain 197 may be relatively short, a larger ratchet wheel 208 is mounted loosely on the same shaft where it can shield the ratchet 55 wheel 207 from its driving pawl 209 except at the one deep notch 210 in ratchet 208; this notch is deep enough to permit the pawl 209 to enter the teeth of the ratchet 207. The pawl 209 is reciprocated by a connection to the lever 190 as is shown in Fig. 2, and from the construction described it is apparent that the chain 197 is driven forward one step in each rotation of the larger 60 ratchet wheel 208. Wherever it is necessary to make any change in the operation of the knitting machine, that is to say, to change the position of a knitting cam, to rack the dial, to operate a yarn changer, or bring the pattern mechanism into action or put it out of action, the chain 197 is provided with a dog or dogs 211 which, in passing, oscillate a lever 212 which is hinged at 213. The left hand end of this lever 212 (as viewed in Fig. 2) is notched to receive a lever 214, hinged at 215, which is connected to shift two pins 216 and 217, either one of which is thus made to stand 70 75

in the path of the cam 206 on the pin wheel 205; when a dog 211 raises lever 212, pin 216 is thrust into the path of the cam and thereby the pin wheel 205 is moved into position for operating 5 the Geneva wheel 204, and thus operating the master controller; contrari-wise, when the dog 211 passes from underneath the roller on 212 and thus permits this lever 212 to fall again, pin 217 is thrust into the path of cam 206 and thereby 10 the pin wheel 205 is moved out of operation with the Geneva wheel, in a manner which will now be understood.

The multiple and complex changes in machine operation that are provided for in the highly developed machine illustrated, require the machine to operate (or at least it is preferable that it be operated) rather slowly while the changes are being made. I therefore provide a change-speed gearing and so couple it up with the master controller that the machine operates rather slowly while changes in operation are taking place and operates at a higher speed at other times. This increases the daily production in such machines as is evident. This connection may be through 15 the lever 212 which is operated by the pattern chain 197 in starting and stopping the master controller, although other connections may be resorted to. In the present instance the power for driving the machine is applied to the pulley 225, which is fixed to the shaft 226. A sleeve 227, fastened to this shaft, carries at its ends two expanding brake bands 228, which have individual rock shafts 229 for expanding and contracting them. Each of these rock shafts is provided with 20 an operating finger 230 and 231, projecting outwardly, and the two rock shafts are geared together as illustrated in Fig. 23, so that only one of the brake bands is expanded at a time. Outside the left-hand (Fig. 22) brake band is a sleeve 25 carrying the miter gear 232 which meshes with the driving gear 233 carried by shaft 234; this shaft also carries a gear 235 meshing with the teeth in the outer edge of the cam cylinder 8 for driving the latter. Hence it is apparent that 30 when the left-hand brake band is expanded, the miter gear 232 is driven at the same speed as the power shaft 226, and the cam cylinder and dial cap are driven at a correspondingly high speed. When this left-hand brake band is contracted 35 however, and the right-hand brake band is expanded, thereby a sleeve outside this right-hand brake band is coupled to the power shaft 226, and thereby a gear 236 on this sleeve acts through reduced speed gears 237 to drive the miter gear 55 232; whence expanding the right-hand brake band (as viewed in Fig. 22) causes operation of the knitting machine at a lower speed. To operate the fingers 230 and 231 and thus bring one brake band or the other into action, a hinged yoke 238 60 and, coupled thereto, a sliding block, are provided; the yoke is connected to the sliding rod 219 and in one position of this rod the block is struck by the brake band finger 230, the latter being thus knocked over, and in another position 65 of the sliding rod 219 the block is so placed as to be struck by the brake band finger 231. Thus in one position of the rod 219 the left-hand brake band is brought into operation and in the other position the right-hand brake band is brought 70 into operation. By connecting this rod 219 to the lever 212 (for example, through lever system 218) the machine is caused to operate at high speed (232 coupled direct to the drive shaft 226) when only knitting is being done (i. e., when 75 there is no dog 211 of the pattern chain 197 under-

neath the roller of the lever 212) and is caused to operate at a much slower speed, a speed proper for enabling the changes in machine operations to take place satisfactorily (miter gear 232 coupled to drive shaft 226 through the speed reducing gear 236—237) while the changes are actually being made (a dog 211 of the pattern chain 197 being under lever 212). 5

During the operation of changing yarns, the dial stitches should be formed by the dial stitch cams 26, rather than by the dial stitch cams 24; this to assure the entry of the new yarn into the cylinder needles. Accordingly, at least as a safety measure, I prefer as a detail to add at each feed a lever 171 (Fig. 6) to engage a pin 172 on the dial cam levers 44 and with its outer end placed in the plane of both the finger levers 156 and 157 of the associated yarn-changing mechanism. Thus when one of the fingers levers of the yarn-changing mechanism is actuated to put 20 a new yarn into action, the same bob-pin 169 which brings this about is also struck by the adjacent lever 171 and this places the associated dial stitch cam 26 in the desired position. 25

In advance of each of the trick wheels 80 or 25 skip operators, it is well to advance the dial needles to tuck position to open their latches; otherwise the latches may catch the yarn guide plate 250 of the corresponding feed in some instances. This is accomplished by a suitable shaping of 30 the race of the needle butts of the dial needles, as indicated at 251 in Fig. 9. At at least one of these points where the dial needles are advanced to open their latches, it is well to provide a latch 35 opener, and to prevent injury in case any latch sticks, or in case any needle is raised up high enough to strike the latch opener, I prefer to mount the latch opener 252 in a yielding manner, and preferably so that it can yield both tangentially of the dial cap and in an upward direction. 40 For this purpose, the latch opener 252 is carried by a bracket 253 which is rotatably mounted on the inclined post 254, but is normally held so that the point 252 is in latch opening position by spring 255. Preferably also, at the 45 latch opener I provide a guide 256 (Fig. 13) for pressing the dial needles down into their slots in the dial.

It will be understood of course that my invention is not limited to the details of construction 50 illustrated, and described above, except as appears hereinafter in the claims.

I claim:

1. In a multi-feed circular rib knitting machine, sliding latch needles differing among themselves in form, the needles of different forms being intermixed in one needle bed and also intermixed in another needle bed, a needle-projecting cam at one feed operable on needles of one form in one bed, a needle-projecting cam at a second feed operable on needles of another form in the same bed, a needle-projecting cam at the first mentioned feed operable on needles of one form in said another needle bed, and a needle-projecting cam at the second mentioned feed operable 60 on needles of another form in said another needle bed, said cams of the first mentioned feed on the one hand and said cams of the second mentioned feed on the other being movable to and from clearing position alternately, whereby fabric of one 65 relation between the dial and cylinder stitches is producible at the first mentioned feed and fabric of another relation between its dial and cylinder stitches is producible at the second mentioned feed. 70 75

2. In a multi-feed circular rib knitting machine, sliding latch needles having high butts, sliding latch needles having low butts, high and low butt needles being intermixed in the dial and 5 also in the cylinder, a cam at one feed operable on only the high butt dial needles, a cam at a second feed operable on the low butt dial needles, a cam at one of said two feeds operable on only the high butt cylinder needles, and a cam at the 10 other of said feeds operable on the low butt cylinder needles, said cams of the two feeds being movable alternately to and from position where they act on needles, whereby fabric having one relation between its dial and cylinder stitches is 15 producible by the use of the said cams at one of said two feeds and fabric having another relation between its dial and cylinder stitches is producible by the use of the said cams at the other of said two feeds.
- 20 3. In a multi-feed circular rib knitting machine, sliding latch needles differing among themselves in form, the needles of different forms being intermixed in the dial and also intermixed in the cylinder, a needle-projecting cam at one feed 25 operable on dial needles of one form, a needle-projecting cam at a second feed operable on dial needles of another form, a needle-projecting cam at the first mentioned feed operable on cylinder needles of one form, and a needle-projecting cam 30 at the second mentioned feed operable on cylinder needles of another form, means for moving said cams of said one feed on the one hand and said cams of the second feed on the other hand to and from operating position alternately, where- 35 by fabric of one relation between the dial and cylinder stitches is producible at the first mentioned feed and fabric of another relation between its dial and cylinder stitches is producible at the second mentioned feed, and means for project- 40 ing selectively, at each pass of each feed, all the needles of one of said needle banks.
4. In a multi-feed circular rib knitting machine, sliding latch needles having high butts, sliding latch needles having low butts, high and 45 low butt needles being intermixed in the dial and also in the cylinder, a cam at one feed operable on only the high butt dial needles, a cam at a second feed operable on the low butt dial needles, a cam at one of said two feeds operable on only the high butt cylinder needles, and a cam at the 50 other of said feeds operable on the low butt cylinder needles, all the cams of one of said two feeds being movable from operative position alternately with all the cams of the other of said feeds, whereby fabric having one relation between its dial and cylinder stitches is producible at one of said two feeds and fabric having another relation 55 between its dial and cylinder stitches is producible at the other of said two feeds, means for moving said cams of one of said needle banks to inoperative position, and means for selectively operating all the needles of said one of the needle banks, at each pass of said two feeds.
5. In a multi-feed circular rib knitting machine, sliding latch needles differing among them- 60 selves in form, the needles of different forms being intermixed in the dial and also intermixed in the cylinder, a needle-projecting cam at one feed operable on dial needles of one form, a needle- 65 projecting cam at a second feed operable on dial needles of another form, a needle-projecting cam at the first mentioned feed operable on cylinder needles of one form, and a needle-projecting cam at the second mentioned feed operable on cylinder needles of another form, all the needle-project- 70
7. In a circular rib knitting machine, sliding needles in one of the needle beds, means for selectively projecting said needles part way to their clearing positions, a cam to the rear of said means for projecting said needles to their clearing positions, another cam also to the rear of said means for returning the partly projected needles toward their rest positions, said two cams being movable into and out 75 of action, and a cam to the rear of said two cams movable into and out of action for projecting needles of said bed to their clearing positions, the last mentioned cam being located so far to the rear of said two cams as to be able to project needles returned toward their rest positions by the second mentioned cam.
8. In a multi-feed circular rib knitting machine, sliding latch needles differing among them- 80 selves in form, the needles of different forms being intermixed in at least one of the needle banks, means at each of two feeds for selectively projecting the needles of said needle bank part way to their clearing positions, a cam to the rear of each of said means for projecting the partly projected needles to their clearing positions, a cam to the rear of each of said means for returning the partly projected needles toward their rest positions, a needle-projecting cam at one feed, to the rear of the aforementioned cams of that feed, operable to project said needles of one form to clearing positions, and a needle-projecting cam at the other of said feeds, to the rear of the aforementioned cams of said another feed, for 85 projecting said needles of another form, said cams being movable toward and from their operating positions.
9. In a circular rib knitting machine having sliding latch needles, cam means for projecting the needles of one needle bank to clearing position, a stitch cam associated therewith, a pattern mechanism to control selective knitting by the needles of the other needle bank, a second stitch cam on the first mentioned needle bank in advance of the first mentioned stitch cam thereof, said second mentioned stitch cam being movable into and out of operating-position, a yarn changer in the feed containing said cams, and means associated with the yarn changing mecha- 90

nism for having the second mentioned stitch cam in action while yarns are being changed.

5. 10. In a circular rib knitting machine adapted to knit a plurality of kinds of plain rib fabric and also to knit a fabric patterned on its face by selective knitting from a plurality of yarns, means for feeding a plurality of yarns simultaneously, a plurality of stitch-forming elements at each of the needle beds differing among themselves in form at each bed, a plurality of cams 10 to actuate said stitch-forming elements of one of the beds to cause knitting thereat, a plurality of cams to actuate said stitch-forming elements of the other of said beds to cause knitting thereat 15 in cooperation with the knitting at the first mentioned bed, each of said plurality of cams including at least one cam operable on stitch-forming elements of one form and another cam operable on stitch-forming elements of another 20 form, means to render at least said another cams ineffective without rendering said one cams ineffective, the said one cam of both beds being capable of being effective while said another cam of both beds is ineffective, means to render said one cam of both beds ineffective when said another cam of both beds is ineffective, said stitch-forming elements of different forms being intermixed at both of said beds in such a manner 25 as to produce one of the desired plain rib fabrics

when said one cam of both beds is effective and said another cam of both beds is ineffective, and to produce a second desired plain rib fabric when said another cam of both beds is effective, means to act on said stitch-forming elements of 5 one of said needle beds to cause, in individual rotations of said means for feeding a plurality of yarns, and in a substantially regular manner, a part of all forms of said stitch-forming elements to form stitches from one of said yarns 10 and other of said stitch-forming elements to form stitches from another of said yarns, pattern means to act on said stitch-forming elements of the other of said needle beds to cause the same, in individual rows of stitches formed at said 15 other bed, to form some of the stitches from one of said yarns and to form the remainder of the stitches from the other or others of said yarns as the desired pattern requires, and means to render said pattern means, and said means which 20 acts on all forms of the stitch-forming elements of the first mentioned needle bed in a substantially regular manner, ineffective when any of said cams is effective, and to render the same effective when all the cams directing operation 25 of said stitch-forming elements to form plain fabrics are ineffective.
